UNITED STATES PATENT OFFICE

MAURICE SANDERS, OF ARVERNE, NEW YORK, ASSIGNOR TO IDEAL NOVELTY & TOY CO., OF BROOKLYN, NEW YORK, A CORPORATION OF NEW YORK

DOLL

Application filed August 20, 1929. Serial No. 387,124.

My invention relates to a new and improved doll.

One of the objects of my invention is to provide a doll having hollow and elastic rubber arms and legs and a relatively rigid body portion, said body portion being preferably stuffed.

Another object of my invention is to provide a doll having a relatively rigid body portion and relatively flexible and resilient arm and leg portions.

Other objects of my invention will be set forth in the following description and drawings which illustrate a preferred embodiment thereof, it being understood that the above general statement of the objects of this invention is intended merely to generally explain the same and not to limit it in any manner.

20 Fig. 1 is a perspective view showing the improved doll in one of the positions which it can be made to assume.

Fig. 2 is a side elevation.

25 Fig. 3 is a detail elevation partially in section, showing a leg member.

Fig. 4 is a diagrammatic view showing how a hollow limb member is molded.

Fig. 5 is a view of the blank for forming the main part of a leg member.

30 Fig. 6 is a perspective view of a blank for forming the foot portion of a leg member.

Fig. 7 is a detail view partially in elevation showing how compressed air is utilized to release a limb member from the core used in molding the same.

35 Fig. 8 is an elevation showing the injector utilized for applying compressed air for this purpose.

It has been known for many years to provide rubber dolls having hollow bodies made of rubber, said bodies having integral rubber arm and leg members. However, such dolls were not life-like, because the entire doll was made of two halves vulcanized together, and the arms and legs were not jointed to the body portion.

40 It has also been known for many years to provide ordinary dolls with leg and arm members provided with joints, to enable life-like effects to be secured.

According to my invention, a doll having a body portion of relatively fixed shape is provided with one or more limb members made of hollow rubber, so that the hollow rubber limb member or members can be 55 readily bent or twisted with respect to the body portion thereof, in order to enable numerous life-like effects to be secured.

The doll is provided with an ordinary fabric body B having stuffing S whereby said body B is maintained in normal fixed shape. The stuffing S may be tight enough to cause the body B to be relatively stiff or rigid, or said stuffing S may be made as loose as desired. The head portion of the doll is affixed 60 in the usual manner.

In the preferred embodiment, the leg members L and the arm members A are formed of hollow rubber, save that the finger portions and the toe portions are preferably made of 70 solid rubber.

Since the method of manufacturing the arm members A and the leg members L is substantially the same, I have only illustrated the method of manufacture of a leg member 75 L. For this purpose an ordinary two-part mold consisting of two like members M Ma is employed. Each of these mold members M Ma is provided with a depression which corresponds in shape and size to one-half 80 of the leg member L. A blank 2 of uncured rubber which has the flat shape shown in Fig. 5, is utilized to form each of the hollow portions of a leg member, and a flat blank 3 shown in Fig. 6 and also preferably made 85 of unvulcanized rubber, is utilized to form a half of each foot portion.

In order to form a leg portion, blanks 2 and 3 are placed in proper position in one of the mold members M. The core C is then 90 placed in proper position. In order to get quantity production, it is to be understood that a number of said cores C project from a common base 5. Additional blanks 2 and 3 are then placed in proper position upon 95 the core C or in the corresponding recess of the second mold member Ma. Since the blanks 2 and 3 are unvulcanized and relatively plastic, they spread under the pressure applied to them until their edges meet and 100

join so as to form a complete leg or arm member. The leg or arm member so formed is seamless although in some cases a line is visible upon the completed leg or arm member showing where the blanks have spread under pressure until their edges meet.

As shown in Fig. 4, each respective pair of mold members **M** and **Ma** meet along a line 10 and the mold member **Ma** can be provided with a dowel pin 8 which fits into a corresponding recess 9 of the mold member **M** in order to cause the parts to properly register.

The hand and feet portions **H** and **F** of the limbs are preferably hollow, but the finger and toe portions are preferably solid.

Each of the cores **C** is preferably formed from a single piece of material and said cores are formed with recesses so that corresponding transverse recesses or grooves 11 are formed in the leg portions **L**.

After the limb members have thus been molded, lines are sometimes visible corresponding to the lines 10, as indicating where the plastic unvulcanized rubber blanks have joined to produce the complete article. Of course, the unvulcanized rubber blanks may have a vulcanizing ingredient therein, and they are vulcanized under heat and pressure while they are within the mold members **M**, and while the cores **C** are in position.

After the limb members have thus been completed and vulcanized, it is necessary to remove them from the cores **C**.

It has been found very difficult to do this on a practical commercial scale.

Hence, I utilize a hollow needle 16 having a hose 17 which is connected to a source of compressed air, and provided with a valve having a head 18. This needle has a narrow outlet end which can be readily inserted between each limb member and the core **C** thereof. The compressed air which is thus forced between each limb member and the core thereof, causes the elastic limb member to expand, so that it can be readily stripped from its corresponding core member. Rigid collars 1 can be readily inserted in the ends of the leg members **L** and these collars 1 may be made hollow and may be provided with noise-making devices 21 which make a sound when the hollow leg members **L** are squeezed.

As shown in Fig. 3, the fabric material of the body portion **B** has its end located within the transverse recesses 11 of the leg members **L** so that a suitable adhesive can hold the leg members **L** in position. The arm members **A** are also secured by adhesive to shoulder portions 19 which are suitably jointed to the body portion **B**, by means of any suitable universal joint or the like. The flexible rubber leg members are also connected to inner end portions which are connected to the body of the doll by joints permitting free movement. As shown in Figs. 2 and 3,

each limb member **L** extends above the joint or knee-cap portion of the respective limb, so that the major part of the limb is composed of hollow, bendable rubber, without any insert. This permits the limb to be bent and twisted, in order to produce the life-like effect illustrated in Fig. 1. The limb member **L** interfits with a stuffed limb extension of the stuffed body, as shown in Fig. 2. This stuffed limb extension can be bent, in order to secure said life-like effect.

Since the body portion **B** is relatively non-bendable, numerous unique effects can be secured by twisting or bending the limb members, one of these unique and life-like effects being shown in Fig. 1. It will be noted that the hollow limb member is free from any inner device, such as a spring or the like, which would be sufficiently rigid to prevent said limb member from being bent or twisted.

While I have shown my invention as applied to a complete doll, it is obvious that the invention comprises numerous valuable sub-combinations which could be separately utilized.

It will be noted that the limb members are made of resilient and readily bendable rubber, instead of the hard rubber which has been previously proposed.

I have shown a preferred embodiment of my invention, but it is clear that numerous changes and omissions can be made without departing from its spirit.

I claim:

1. A doll having a body portion and also having a hollow limb member which is formed of resilient rubber so that said limb member can be readily bent and twisted, the inner end of said limb member having a rigid end member located therein, said rigid end member being provided with a transverse groove into which a part of the adjacent portion of the limb member enters.

2. A doll having a stuffed fabric body of substantially permanent shape, and a limb for said body, said limb comprising a stuffed limb-extension projecting from said body, said extension interfitting with a hollow limb member made of transversely bendable and resilient rubber, said transversely bendable rubber limb member constituting the major portion of said limb, and extending inwardly of the joint-portion of said limb, so that said inwardly extending portion can be transversely bent and squeezed, said hollow limb member being free from any inner part which would prevent the transverse bending thereof.

3. A doll having a stuffed fabric body of substantially permanent shape, and a limb for said body, said limb comprising a stuffed limb-extension projecting from said body, said extension interfitting with a hollow limb member made of transversely bendable and

resilient rubber, said transversely bendable rubber limb member constituting the major portion of said limb, and extending inwardly of the joint-portion of said limb, so that
5 said inwardly extending portion can be transversely bent and squeezed, said hollow rubber limb member being provided with a rigid insert at the inner end thereof, said hollow limb member being free from any
10 inner part which would prevent the transverse bending thereof.

4. A doll having a stuffed fabric body of substantially permanent shape, and a limb for said body, said limb comprising a stuffed
15 limb-extension projecting from said body, said extension interfitting with a hollow limb member made of transversely bendable and resilient rubber, said transversely bendable rubber limb member constituting
20 the major portion of said limb, and extending inwardly of the joint-portion of said limb, so that said inwardly extending portion can be transversely bent and squeezed, said hollow rubber limb member being pro-
25 vided with a rigid insert at the inner end thereof, said insert having a noise-producing device so that a noise can be produced by squeezing said rubber limb member, said hollow limb member being free from any in-
30 ner part which would prevent the transverse bending thereof.

5. A doll having a stuffed fabric body of substantially permanent shape and a hollow limb member connected to said body, said
35 limb member being made of transversely bendable and resilient rubber which can be readily squeezed and which extends inwardly of the joint portion of the respective limb, said hollow limb member having a rigid in-
40 sert at its inner end, said hollow limb member being free from any inner part which would prevent the free transverse bending of the rubber.

In testimony whereof I affix my signature.
45 MAURICE SANDERS.
